UNITED STATES PATENT OFFICE.

ULRICH F. SCHAEFFER, OF NEW YORK, ASSIGNOR TO PRAHAR & BROTHER,
OF BROOKLYN, NEW YORK.

DESIGN FOR A BUCKLE.

SPECIFICATION forming part of Design No. 21,395, dated March 8, 1892.

Application filed February 3, 1892. Serial No. 420,230. Term of patent 3½ years.

To all whom it may concern:

Be it known that I, ULRICH F. SCHAEFFER, a citizen of the United States, residing at New York city, in the county and State of New York, have invented and produced a new and original Design for a Buckle, of which the following is a full, clear, and exact specification, reference being had to the accompanying drawing, forming part thereof, which represents a front elevation of a buckle embodying the features of my design.

The design consists of a medallion A, upon which is delineated a representation of Christopher Columbus. The representation of shields B and B' is arranged above and below the medallion, one shield bearing upon its face crossed bars and the representation of a turret of a castle and the other shield the stars and stripes. Panels D and D' appear

at each side of the medallion and between 20 the shields, and panels F are also arranged at the extreme top and bottom of the buckle. Of these two latter panels the upper one contains the number "1492" and the lower one the name "Columbus" and the number "1892." 25 The side surfaces of the buckle represent chains E of leaf-like scrolls, apparently connecting the outer portions of the shields; but the dates and the name of Columbus constitute no portion of the design. 30

I claim—

The design for a buckle, substantially as herein shown and described.

ULRICH F. SCHAEFFER.
